UNITED STATES PATENT OFFICE

2,064,659

EVAPORATOR FOR REFRIGERATING MACHINES

Frank T. Grothouse, Fort Wayne, Ind., assignor to General Electric Company, a corporation of New York

Application February 2, 1935, Serial No. 4,653

16 Claims. (Cl. 62—126)

My invention relates to evaporators of the flooded type for refrigerating machines.

Evaporators of the flooded type usually include a header and an extended refrigerant passage 5 communicating therewith. Liquid refrigerant is supplied to the evaporator from a compressor and condenser unit, or other refrigerant liquefying apparatus. Such liquid refrigerant passes through the refrigerant passage and is vaporized 10 by the absorption of heat from articles to be cooled, which are contained in a compartment in which the evaporator is located. In many types of refrigerators, particularly in those designed for household use, the evaporator is ordinarily 15 provided with a freezing compartment located in or adjacent the main food storage compartment. Such evaporators are preferably constructed of sheet metal both because of the low manufacturing cost, and also because of the 20 pleasing appearance of the finished product. When such evaporators are constructed of sheet metal the header and refrigerant circulatory passages may conveniently be formed by indentations in one or both of the complementary sheet 25 metal portions making up the evaporator.

It is an object of my invention to provide an evaporator of the flooded type for refrigerating machines including a plurality of headers and a refrigerant circulatory passage communicating 30 therewith so arranged that they occupy a minimum amount of the usable storage space in the enclosure formed by the evaporator, and yet effectively utilize the evaporator surfaces for the 35 transference of heat from articles to be cooled. It is a further object of my invention to provide an improved sheet metal evaporator for refrigerating machines made up of complementary portions of sheet metal and forming at least three side walls of a freezing compartment.

40 Further objects and advantages of my invention will become apparent as the following description proceeds and the features of novelty which characterize my invention will be pointed out with particularity in the claims annexed to and forming a part of this specification.

45 For a better understanding of my invention, reference may be had to the accompanying drawing in which Fig. 1 is a front elevation of a portion of a refrigerating machine, the refrigerating machine including an evaporator embodying my invention; Fig. 2 is a perspective view of an evaporator embodying my invention; Fig. 3 is a sectional view on the line 3—3 of the evaporator 50 shown in Fig. 2; and Fig. 4 is a schematic representation

of the refrigerant circulatory system of the evaporator shown in Fig. 2.

Referring to the drawing, in Fig. 1 I have shown a refrigerating machine including an evaporator embodying my invention. In this refrigerating 5 machine a motor and compressor are arranged in a hermetically sealed casing 10. Gaseous refrigerant is compressed by the rotor driven compressor in the casing 10 and is discharged into a natural draft air cooled condenser 11 where it is 10 liquefied. The liquefied refrigerant flows from the condenser 11 through a flow controlling float valve 12 into a liquid line 13, which supplies liquid refrigerant to an evaporator 14. The evaporator 14 comprises a horizontal U-shaped body made of 15 two sheets or portions of sheet metal 15 and 16, preferably of steel, welded together with their adjacent surfaces in contact and forming vertical side walls of the evaporator 14. Complementary indentations 17 and 18 in the sheets 15 and 16, 20 respectively, form a horizontal cylindrical header 19 in one of the side walls of the freezing compartment formed by the evaporator 14. Horizontal cylindrical headers 20 and 21 are formed in the remaining side walls of the evaporator 14 25 by complementary indentations in the sheets 15 and 16 similar to the indentations 17 and 18. The headers 19, 20, and 21 are in substantial horizontal alignment and are connected in series above the level of liquid refrigerant therein by 30 pressure equalizing passages 22 and 23 formed by indentations in the exterior sheet 15. The headers 19, 20, and 21 are also connected in series below the level of liquid refrigerant therein by 35 liquid refrigerant equalizing passages 24 and 25, which are also formed between the sheets by indentations in exterior sheet 15. A series of headers is thus formed about the upper edges of the evaporator 14, these headers being arranged to 40 occupy a minimum amount of the usual storage space within the evaporator 14, while at the same time they provide ample header space for the separation of liquid and vaporized refrigerant. The headers 19 and 21, which are located at the extremities of the series of headers thus formed, 45 are connected by a tortuous refrigerant circulatory system including passages extending about the walls of the evaporator 14, the passages being formed between the sheets by indentations in the sheet 15. This system of passages includes 50 the refrigerant circulatory passage 26, which communicates with the header 19 below the normal liquid level therein, and the refrigerant passage 27 communicating with the header 21 below the normal liquid level therein. The passages 26 55

and 27 are connected in series by a branched section made up of the parallel passages 28 and 29. The sheets 15 and 16 are welded or otherwise secured together along their peripheral edges and 5 between the refrigerant passages, and the sheets are then bent in a horizontal U-shape, thus forming three vertical side walls of a freezing compartment.

The vertical front edges of the sheets 15 and 16 10 are bent to form inwardly extending flanges 30 and 31, reinforcing the side walls and providing a suitable support for freezing shelves 14a and 14b. The flanges 30 and 31 are provided with pairs of ears 32, 33, and 34, 35, respectively. The 15 two horizontal shelves 14a and 14b within the evaporator 14 are each made of portions of sheet metal, such as steel or other heat conducting material. The lower shelf 14b is made of two complementary sheets of metal 36 and 37. A sinuous 20 indentation is formed in the lower sheet 37 thus providing a refrigerant circulatory passage 38 between the sheets for the lower shelf. The sheets 36 and 37 are welded or otherwise joined together along their peripheral edges and between 25 the indentations formed therein. A supporting and reinforcing flange 39 is formed along the front edge of the lower shelf and is secured to the ears 33 and 35 on the flanges 30 and 31, respectively, by bolts 40 and 41, the rear end of 30 the shelf being supported by conduits 48 and 49, and by a bracket 36a welded to the shelf and the rear wall of the evaporator. The upper shelf 14a is made of complementary sheets of metal 42 and 43, a sinuous indentation being formed in the 35 lower sheet 43 to provide a refrigerant circulatory passage 44 between the sheets for the upper shelf. The refrigerant circulatory passage 44 has not been shown in Fig. 2 in order that the refrigerant circulatory system in the vertical walls of the 40 evaporator may be more clearly viewed, the passage 44 is, however, clearly shown in Fig. 4. The sheets 42 and 43 are welded or otherwise secured together along their peripheral edges and between the indentations formed therein, the front edge 45 of the shelf being provided with a reinforcing flange 45. The upper shelf 14a is supported at the front thereof by securing the flange 45 by bolts 46 and 47 to the ears 32 and 34 on flanges 30 and 31, respectively. The rear of the shelf 14a 50 is supported by conduits 13 and 48, and by a bracket 42a welded to the shelf and the rear wall of the evaporator. An evaporator having a very pleasing and symmetrical appearance is thus provided while at the same time it is so sturdily constructed that it will withstand hard usage.

The headers 19, 20, and 21 are maintained, during normal operation of the machine, about half full of liquid refrigerant as indicated in Fig. 3, the headers and passages forming a refrigerant 60 containing chamber in the walls of the evaporator 14. The refrigerant circulatory passages 38 and 44 in the shelves 14b and 14a, respectively, as well as the refrigerant circulatory passages 26, 27, 28, and 29 in the side walls of the evaporator 65 14 are thus maintained flooded with liquid refrigerant. The liquid and vaporized refrigerant separate in the headers 19, 20, and 21, the vaporized refrigerant accumulating above the level of the liquid refrigerant in the headers. The vaporized refrigerant accumulated in the headers 20 70 and 21 passes through the series pressure equalizing passages 22 and 23, which are connected thereto above the normal liquid level therein, to the header 19 from which it returns to the motor 75 driven compressor contained in the casing 10

through a suction line 53. The suction line 53 is connected to the header 19 above the normal liquid level therein.

Liquid refrigerant from the liquid line 13 is supplied to the upper shelf refrigerant passage 5 44, which is connected in series with the sinuous refrigerant passage 38 in the lower shelf by the conduit 48. It will be noted that the liquid line 13 and the conduit 48 are connected to the ends of the passage 44 in the upper shelf 14a by embossments 44a and 44b, respectively, thus forming a support for the rear edge of the shelf as the conduits 13 and 48 extend through holes in the rear wall of the evaporator 14. After passing through the sinuous passage 38 in the lower shelf 15 14b, the liquid refrigerant is discharged therefrom into a conduit 49. The conduits 48 and 49 extend through holes in the rear wall of the evaporator 14 and are connected to the ends of the passage 38 in the lower shelf 14b by embossments 20 38a and 38b, respectively, thus forming a support for the rear edge of the shelf. Since the fresh incoming refrigerant supplied to the evaporator 14 is first circulated through the series connected 25 passages 38 and 44, the shelves 14a and 14b provide a sharp freezing zone in which trays of water or the like to be frozen may conveniently be supported.

Liquid refrigerant is injected from the conduit 49 through branched ends 50 and 51 thereof, into 30 the parallel refrigerant circulatory passages 28 and 29. The upper portion of the conduit 49 and the branched ends 50 and 51 thereof are located in the passages 28 and 29, respectively, between the sheets 15 and 16, which form the vertical walls 35 of the evaporator 14. The injection of liquid refrigerant from the ends 50 and 51 of the conduit 49 induces a positive circulation of liquid refrigerant about the vertical walls of the evaporator 14 through the passages 28 and 29 into 40 the passage 27 from which it is discharged into the header 21 as indicated by the arrows in Fig. 4. Such injection of liquid refrigerant from the ends 50 and 51 of the conduit 49 also induces a 45 recirculation of liquid refrigerant from the headers 19, 20, and 21 connected in series by the refrigerant equalizing passages 24 and 25, through the passage 26 and then through the passages 28 and 29 past the injection points 50 and 51. As the liquid refrigerant circulates through the 50 passages 24 to 29, inclusive, it is partially vaporized by the absorption of heat from the food storage compartment 52 in which the evaporator 14 is located. Such vaporized refrigerant is carried along by the positively circulating liquid refrigerant in the path described, until it reaches one 55 of the headers 19, 20, or 21 in which it is allowed to separate from the liquid refrigerant and accumulates above the surface thereof. It will thus be seen that I provide an efficient arrangement 60 for positively circulating and recirculating the liquid refrigerant contained in the evaporator 14 until it is vaporized by the absorption of heat.

The evaporator 14 is supported from the removable top wall of the food storage compartment 65 52 by bolts or other securing means extending through holes 54 in the inturned ears 55 formed along the upper edge of the vertical walls of the evaporator 14. The lower portion of the evaporator 14 provides a storage space surrounded on five sides by refrigerated walls, so that articles contained therein may be rapidly cooled or frozen. The upper portion of the evaporator 14 provides nearly as effective an arrangement for rapid heat transfer as the storage space there 70 75

provided is surrounded on four sides by refrigerated walls and since the top of the evaporator 14 is located closely adjacent the top wall of the compartment 52 there will be only a limited circulation of warmer air down through the top of the evaporator. The surfaces of the evaporator are designed to adequately cool the food compartment 52.

By utilizing a plurality of headers 18, 20 and 21, ample space is provided for the separation of liquid and vaporized refrigerant in relatively quiet zones, so that any liquid refrigerant remaining in the headers may be efficiently recirculated through the walls of the evaporator 14 and thus effectively utilized. These headers are so distributed that they occupy a minimum of usable storage space within the enclosure formed by the evaporator 14.

While I have shown a particular embodiment 20 of my invention in connection with a compression refrigerating machine, I do not desire my invention to be limited to the particular construction shown and described and I intend in the appended claims to cover all modifications within 25 the spirit and scope of my invention.

What I claim as new and desire to secure by Letters Patent of the United States, is:

1. An evaporator of the flooded type for refrigerating machines comprising a plurality of headers, means including pressure equalizing passages for connecting said headers in series above the normal liquid levels therein, means including liquid refrigerant equalizing passages for connecting said headers in series below the normal liquid levels therein, means including a refrigerant circulatory passage communicating with one of said headers at one end and with another of said headers at its other end for containing liquid refrigerant, and means communicating with said circulatory passage remote from said headers for producing a recirculation of liquid refrigerant from said headers and through said circulatory passage.

2. An evaporator of the flooded type for refrigerating machines comprising a series of headers, means including pressure equalizing passages for connecting said headers in series above the normal liquid levels therein, means including liquid refrigerant equalizing passages for connecting said headers in series below the normal liquid level therein, means including a tortuous refrigerant circulatory passage communicating at its opposite ends with the headers located at the extremities of said series of headers for containing liquid refrigerant, and means injecting liquid refrigerant into said refrigerant circulatory passage intermediate its ends for inducing recirculation of liquid refrigerant through said series of headers and said refrigerant circulatory passage.

60 3. An evaporator of the flooded type for refrigerating machines comprising a series of headers, means including pressure equalizing passages for connecting said headers in series above the normal liquid levels therein, means including liquid refrigerant equalizing passages for connecting said headers in series below the normal liquid levels therein, means including a tortuous refrigerant circulatory passage communicating at its opposite ends with the headers located at the extremities of said series of headers for containing liquid refrigerant, said refrigerant circulatory passage including a branched section intermediate its ends providing a plurality of parallel circulatory passages, and means injecting liquid refrigerant into said parallel circulatory passages

for inducing recirculation of liquid refrigerant through said series of headers and said refrigerant circulatory passage.

4. An evaporator of the flooded type for refrigerating machines comprising complementary sheet metal portions, means for joining said sheet metal portions together, at least one of said sheet metal portions having indentations therein forming a series of headers, at least one of said sheet metal portions having indentations therein forming pressure equalizing passages connecting said headers in series above the normal liquid levels therein and liquid refrigerant equalizing passages connecting said headers in series below the normal liquid levels therein, means including a refrigerant circulatory passage formed in at least one of said sheet metal portions and having one end communicating with one of said headers and its other end communicating with another of said headers for containing liquid refrigerant, and means communicating with said refrigerant circulatory passage remote from said headers for producing a recirculation of liquid refrigerant through said headers and through said refrigerant circulatory passage.

5. An evaporator of the flooded type for refrigerating machines comprising complementary sheet metal portions, means joining said sheet metal portions together, at least one of said sheet metal portions having indentations therein forming a series of headers, a least one of said sheet metal portions having indentations therein forming pressure equalizing passages connecting said headers in series above the normal liquid levels therein and liquid refrigerant equalizing passages connecting said headers in series below the normal liquid levels therein, at least one of said sheet metal portions also having indentations therein forming a tortuous refrigerant circulatory passage communicating at its opposite ends with the headers located at the extremities of said series of headers, and means injecting liquid refrigerant into said refrigerant circulatory passage intermediate its ends for inducing recirculation of liquid refrigerant through said series of headers and said refrigerant circulatory passage.

6. An evaporator of the flooded type for refrigerating machines comprising complementary sheet metal portions, means for joining said sheet metal portions together, at least one of said sheet metal portions having indentations therein forming a series of headers, a least one of said sheet metal portions having indentations therein forming pressure equalizing passages connecting said headers in series above the normal liquid levels therein and liquid refrigerant equalizing passages connecting said headers in series below the normal liquid levels therein, at least one of said sheet metal portions also having indentations therein forming a tortuous refrigerant circulatory passage communicating at its opposite ends with the headers located at the extremities of said series of headers, said refrigerant circulatory passage including a branched section intermediate its ends providing a plurality of parallel circulatory passages, and means injecting liquid refrigerant into said parallel circulatory passages for inducing recirculation of liquid refrigerant through said series of headers and said refrigerant circulatory passage.

7. An evaporator of the flooded type for refrigerating machines comprising complementary sheet metal portions forming three vertical walls of a freezing compartment, means for securing

said complementary sheet metal portions together, at least one of said sheet metal portions having indentations therein forming a header in each of said vertical walls, means including passages connecting said headers for equalizing the distribution of refrigerant in said headers, means including a tortuous refrigerant circulatory passage communicating with at least two of said headers for containing liquid refrigerant, and means injecting liquid refrigerant into said tortuous refrigerant passage for inducing recirculation of liquid refrigerant from said headers through said tortuous passage.

8. An evaporator of the flooded type for refrigerating machines comprising complementary U-shaped sheet metal portions forming three vertical walls of a freezing compartment, means for securing said complementary sheet metal portions together, at least one of said sheet metal portions having indentations therein forming a header in each of said vertical walls, means including passages connecting said headers for equalizing the distribution of refrigerant in said headers, means including a tortuous refrigerant circulatory passage extending between said sheets and communicating with at least two of said headers for containing liquid refrigerant, and means injecting liquid refrigerant into said tortuous refrigerant passage for inducing recirculation of liquid refrigerant from said headers through said tortuous passage.

9. An evaporator of the flooded type for refrigerating machines comprising complementary U-shaped sheet metal portions forming three vertical walls of a freezing compartment, means for joining said sheet metal portions together, at least one of said sheet metal portions having indentations therein forming a header in each of said vertical walls, at least one of said sheet metal portions having indentations therein forming pressure equalizing passages connecting said headers in series above the normal liquid levels therein and liquid refrigerant equalizing passages connecting said headers in series below the normal liquid levels therein, means including a refrigerant circulatory passage formed in at least one of said sheet metal portions and having one end communicating with one of said headers and its other end communicating with another of said headers for containing liquid refrigerant, and means communicating with said refrigerant circulatory passage remote from said headers for producing a recirculation of liquid refrigerant through said headers and through said refrigerant circulatory passage.

10. An evaporator of the flooded type for refrigerating machines comprising complementary U-shaped sheet metal portions forming three vertical walls of a freezing compartment, means for securing said complementary sheet metal portions together, at least one of said sheet metal portions having indentations therein forming a header in each of said vertical walls, at least one of said sheet metal portions having indentations therein forming pressure equalizing passages connecting said headers in series above the normal liquid levels and liquid refrigerant equalizing passages connecting said headers in series below the normal liquid levels therein, at least one of said sheet metal portions having indentations therein forming a tortuous refrigerant circulatory passage communicating at its opposite ends with the headers located at the extremities of said series of headers, and means injecting liquid refrigerant into said refrigerant circulatory passage inter-

mediate its ends for inducing recirculation of liquid refrigerant through said series of headers and said refrigerant circulatory passage.

11. An evaporator of the flooded type for refrigerating machines comprising complementary U-shaped sheet metal portions forming three vertical walls of a freezing compartment, means for securing said complementary sheet metal portions together, at least one of said sheet metal portions having indentations therein forming a header in each of said vertical walls, at least one of said sheet metal portions having indentations therein forming pressure equalizing passages connecting said headers in series above the normal liquid levels therein and liquid refrigerant equalizing passages connecting said headers in series below the normal liquid levels therein, at least one of said sheet metal portions having indentations therein forming a tortuous refrigerant circulatory passage communicating at its opposite ends with two of said headers located in opposite walls of said compartment, said refrigerant circulatory passage including a branched section intermediate its ends providing a plurality of parallel circulatory passages, and means injecting liquid refrigerant into said parallel circulatory passages for inducing the recirculation of liquid refrigerant through said series of headers and said refrigerant circulatory passage.

12. An evaporator of the flooded type for refrigerating machines comprising complementary U-shaped sheet metal portions forming three vertical walls of a freezing compartment, means for securing said complementary sheet metal portions together, at least one of said sheet metal portions having indentations therein forming a header in each of said vertical walls, at least one of said sheet metal portions having indentations therein forming pressure equalizing passages connecting said headers in series above the normal liquid levels therein and liquid refrigerant equalizing passages connecting said headers in series below the normal liquid levels therein, at least one of said sheet metal portions having indentations therein forming a tortuous refrigerant circulatory passage communicating at its opposite ends with headers located in opposite walls of said compartment, a shelf extending across said compartment, means including a refrigerant circulatory passage for cooling said shelf, and means injecting liquid refrigerant from said last mentioned passage into said first mentioned refrigerant circulatory passage intermediate the ends of the latter for inducing recirculation of liquid refrigerant through said series of headers and said first mentioned refrigerant circulatory passage.

13. An evaporator of the flooded type for refrigerating machines comprising complementary U-shaped sheet metal portions forming three vertical walls of a freezing compartment, means for securing said complementary sheet metal portions together, at least one of said sheet metal portions having indentations therein forming a header in each of said vertical walls, at least one of said sheet metal portions having indentations therein forming pressure equalizing passages connecting said headers in series above the normal liquid levels therein and liquid refrigerant equalizing passages connecting said headers in series below the normal liquid levels therein, at least one of said sheet metal portions having indentations therein forming a tortuous refrigerant circulatory passage communicating at its opposite ends with headers located in opposite

walls of said compartment, said refrigerant circulatory passage including a branched section intermediate its ends providing a plurality of parallel circulatory passages, a shelf extending 5 across said compartment, means including a refrigerant circulatory passage for cooling said shelf, and means injecting liquid refrigerant from said last mentioned circulatory passage into said parallel circulatory passages for inducing recirculation of liquid refrigerant through said series 10 of headers and said first mentioned refrigerant circulatory passage.

14. An evaporator of the flooded type for refrigerating machines, comprising complementary 15 sheet metal portions of a horizontal U-shaped form constituting three vertical walls of a freezing compartment, means for securing said complementary sheet metal portions together, at least one of said sheet metal portions having indentations therein forming refrigerant passages in 20 said walls, a sheet metal shelf provided with a refrigerant circulatory passage extending across said compartment, and means for securing said shelf to said sheet metal portions.

25 15. An evaporator of the flooded type for refrigerating machines comprising complementary sheet metal portions of a horizontal U-shaped form constituting three vertical walls of a freezing compartment, means for securing said com-

plementary sheet metal portions together, at least one of said sheet metal portions having indentations therein forming a tortuous refrigerant passage extending about said walls, said sheet metal portions being provided with inturned 5 flanges along the vertical edges thereof, a sheet metal shelf provided with a refrigerant circulatory passage extending across said compartment, and means for securing said shelf to said inturned flanges.

10 16. An evaporator of the flooded type for refrigerating machines comprising complementary sheet metal portions of a horizontal U-shaped form constituting three vertical walls of a freezing compartment, means for securing said complementary sheet metal portions together, at least one of said sheet metal portions having indentations therein forming a tortuous refrigerant passage 15 extending about said walls, said sheet metal portions being provided with inturned flanges 20 along the vertical edges thereof, a plurality of vertically spaced sheet metal shelves provided with refrigerant circulatory passages extending across said compartment, and means for circulating liquid refrigerant through said passages in 25 said shelves in series and then injecting the same in said first mentioned tortuous refrigerant passage.

FRANK T. GROTHOUSE.

CERTIFICATE OF CORRECTION.

Patent No. 2,064,659.

December 15, 1936.

FRANK T. GROTHOUSE.

It is hereby certified that error appears in the printed specification of the above numbered patent requiring correction as follows: Page 3, second column, lines 31 and 53, claims 5 and 6 respectively, for the article "a" second occurrence, read at; and that the said Letters Patent should be read with these corrections therein that the same may conform to the record of the case in the Patent Office.

Signed and sealed this 23rd day of February, A. D. 1937.

Henry Van Arsdale
Acting Commissioner of Patents.
